UNITED STATES PATENT OFFICE.

JENNIE M. COON, OF BATTLE CREEK, MICHIGAN.

AUTOMOBILE SIGNAL LIGHT.

Application filed March 23, 1927. Serial No. 177,627.

This invention relates to an automobile signal light, and particularly to a construction adapted to indicate the intention of the operator to change the condition of movement of the vehicle under his control.

Under the general construction of signal lights it is necessary to provide a special structure of lamp and reflecting means to illuminate the signal designation, and such 10 indications are not readily changeable as conditions of use may require. To obviate such objections I have provided a simple construction of indicating means adapted for application to an ordinary lamp structure and having reflecting faces cooperating with the normal reflector of the lamp so as to concentrate the light rays and project them through the indicating face of the attachment. This attachment may be most 20 conveniently and economically formed from a plate having an indicating face and diverging wings formed with an inner reflecting surface, the entire structure being replaceably supported within an ordinary lamp reflector by the front lens or transparent plate of the lamp. In so forming this attachment it is of particular importance that the reflecting surfaces upon the wings thereof be directed in an inclined plane to the vertical so as to cooperate with the outer rays from the lamp reflector and concentrate them upon the indicating face of the device.

In the application of a signal lamp of this 25 character it is very desirable to control the same in connection with cowl lamps cooperating with each of the signal lamps so as to indicate to an approaching machine the intention of the operator to turn in either direction.

The invention has for an object to provide a novel and improved construction of indicating member for signal lamps comprising a body having an indicating face and wings extended therefrom to engage the reflector of the signal lamp and confine the light rays to the area of the indicating face.

A further object of the invention is to provide a replaceable construction having a central indicating face and oppositely inclined wings diverging therefrom and formed with reflecting inner surfaces adapted to cooperate with the usual parabolic reflector of a lamp.

Another object of the invention is to provide an attachment comprising a plate with

a central indicating face and opposite diverging wings having inclined reflector surfaces adapted to concentrate the light rays upon the indicating face. 60

Other objects and advantages of the invention will be hereinafter set forth and the novel features thereof defined by the appended claims.

In the accompanying drawing:

Figure 1 is a plan showing the application of the invention to a vehicle;

Figure 2 is a vertical detail section of the indicator applied to a lamp;

Figure 3 is a detail perspective of one indicator;

Figure 4 is a similar view of the opposite indicator; and

Figure 5 is a perspective of a modified form of the invention. 75

Like reference numerals designate corresponding parts throughout the several figures of the drawing.

The invention is adapted for application to any desired form of automobile lamp and 80 may either be formed in connection therewith when manufactured or preferably as an attachment adapted to be inserted within the lamp. The latter form of the invention is shown in Figure 2 where the lamp 85 10 is provided with the usual parabolic reflector 11 and bulb 12 at the center thereof, while the outer end of the lamp casing has applied thereto the removable rim 13 carrying the lens or transparent plate 14 at the 90 front of the lamp. Such a casing may be supported in any desired manner, for instance by the adjustable clamp as indicated at 15 which comprises lugs 16 mounted upon the lamp and engaging a plate 17 secured 95 to the fender 18.

Within the lamp just described the signal plate or body 20 is inserted and this comprises the indicating face 21 which as shown in Figures 2, 3 and 4 has applied thereto 100 the designation 22 which may be of any desired character. While the words "Right" and "Left" have been shown in the drawing, it is obvious that other lettering may be applied such as "Stop" or "Slow". This plate is formed with rearwardly diverging wings 23, which are preferably disposed diagonally to the indicating face 21 and upon the inner face of these wings a reflecting surface 24 is provided. The peripheral edges of the wings 23 are preferably 105 curved as at 23^a to conform to the curvature 110

of the parabolic reflector 11 when in contact therewith.

The reflecting surface 24 may be formed by painting or otherwise, and owing to the 5 inclination thereof receives the outer rays from the parabolic reflector and turns them toward the indicating face so as to concentrate the light at that point and prevent the passage of any light above or below the area 10 of the indication. In the application of the invention as an attachment this plate is retained in position within the reflector of the lamp by contact with the lens 14 thereof, as shown in Figure 2, so that it is readily 15 replaceable and permits the use of an ordinary lamp for any preferred indicating or signal purpose.

A modified form of the invention is shown in Figure 5 wherein the body 25 is formed 20 with an opening therethrough in front of which a signal plate 26 is supported by flanges 27 bent from the body. This plate may be of any desired color glass and carries the designation 28 having a transparent or 25 similar lettering. The plate 25 in this instance is provided with the wings 29 similar in construction to those before described and having the inner reflecting surfaces 30.

While the signal lamp so far described 30 may be positioned upon an automobile in accordance with the desired requirements, still a convenient arrangement thereof is shown in Figure 1 wherein lamps bearing opposite directional indications are mounted 35 upon the rear fenders 18 as before described. Separate circuit lines 31 for these lamps extend from a battery 32 or other source of electricity and such circuit is carried through an ammeter 33 and dash lamps 34 40 connected therefrom to controlling switches 35 conveniently disposed upon the steering wheel 36. In each of the circuits 31 a cowl lamp 37 is interposed so that when circuit is made by either switch 35 to the corresponding rear lamp the cowl lamp of such 45 circuit indicates at the front of the machine the direction of turn to be made. The dash lamps in these circuits readily show the condition thereof and the battery and 50 circuits are grounded to the frame of the machine in the usual manner.

The construction presented is of a simple character adapted to be economically manufactured and very effectively applied to the 55 ordinary type of automobile lamp so that when positioned therein either permanently or as an attachment the rays of the lamp are concentrated upon the indicating sur-

face of the plate and obscured from all other portions of the lamp lens. The replaceable mounting of the indicator plate permits the ready change thereof for different characters of signal or the ordinary use of the lamp without such signal indications.

While the specific construction of the lamp and the indicating member has been shown and described, the invention is not confined thereto as changes and alterations may be made without departing from the spirit of 70 the invention as defined by the following claims.

Having thus described my invention, what I claim as new and desire to secure by Letters Patent of the United States, is:—

1. An indicating member for signal lamps including a reflector, said member comprising a body having an indicating face and oppositely disposed wings extended therefrom toward and within the lamp reflector 80 arranged to confine the light rays from a portion of said reflector to the area of said indicating face.

2. An indicating member for signal lamps comprising a body having an indicating face 85 and inclined wings extending therefrom with inner reflecting surfaces disposed opposite the lamp reflector to cooperate therewith and concentrate the light rays upon said indicating face.

3. An attachment for signal lamps for association with the reflector thereof and comprising a plate having a central indicating face and oppositely diverging wings for confining the light rays to the area of 95 said face.

4. An attachment for signal lamps for association with the reflector thereof and comprising a plate having a central indicating face bearing a signal designation, and 100 oppositely disposed wings having inner reflecting surfaces arranged to cooperate with the lamp reflector and concentrate the light rays upon the indicating face.

5. An indicating attachment for signal 105 lamps for association with the reflector thereof and comprising a central portion having an indicating designation thereon, and oppositely diverging wings bent therefrom and formed with curved edges adapted to conform to the surface of the lamp reflector.

In testimony whereof I affix my signature.

MRS. JENNIE M. COON.
